GAS BOTTLE CARRYING RACK FOR TRAILERS

Harold W. Norris, 12-18 Sylvan Ave., Battle Creek, Mich.

Filed June 7, 1960, Ser. No. 34,541

8 Claims. (Cl. 211—74)

This invention relates to improvements in gas bottle carrying rack for trailers. The principal objects of this invention are:

First, to provide an inexpensive rack for securely clamping a pair of metal gas storage bottles on the frame of a mobile home or trailer.

Second, to provide a bottle rack with a base which laterally interlocks with the bases of two gas bottles and with a releasable upper clamp which grips the upper necks of the bottles to prevent lateral and vertical displacement thereof and which supports gas connections and regulating fixtures for cooperation with the bottles.

Third, to provide a bottle rack in which the gas connections and regulator are supported from the clamp structure which secures the gas bottles to the base of the rack so that separate regulator supporting structure is unnecessary.

Other objects and advantages of the invention will be apparent from a consideration of the following description and claims. The drawings of which there is one sheet illustrating a highly practical form of the bottle rack operatively installed on the tongue or frame of a trailer.

Fig. 1 is a fragmentary front elevational view of the rack operatively associated with a pair of gas bottles. Portions of the coating trailer frame are broken away in cross section.

Fig. 2 is a fragmentary vertical cross sectional view taken along the plane of the line 2—2 in Fig. 1.

Mobile homes and trailers are commonly supplied with heating and cooking fuel in the form of liquified petroleum gas which is delivered in demountable metal tanks called gas bottles and it is common to provide a supporting and retaining frame or rack on the tongue or frame at the front of the trailer for removably supporting these gas bottles. The drawings illustrate the converging front tongue or frame members 1 of a trailer with a pair of generally cylindrical gas bottles 2 mounted thereon. The bottles have short cylindrical lower necks 3 and relatively higher segmental cylindrical shields 4 which enclose and protect the detachable connections to the bottles. These bottles with their upper and lower necks are more or less standardized in the compressed gas supply trade and the rack of the invention is arranged to cooperate with these standardized bottles.

The rack consists of generally rectangular base plate 5 having upstanding front and rear flanges 6 which are notched or cut away toward each end as at 7 to nestingly and laterally retainingly receive the lower necks 3 of the gas bottles. The base plate 5 is detachably but securely anchored to the frame members 1 by means of J hooks 8 hooked under the frame members and passed upwardly through holes provided therefor in the base plate to clamping nuts 9.

Near its center the base plate 5 is provided with an upwardly offset boss 10 with a central hole therein which passes the shank of a hold down bolt or rod 11. The upper end of the hold down rod has an eye or loop 12

formed therein and a nut 13 and lock washer 14 on the lower end of the hold down bolt prevents upward displacement of the hold down bolt.

The upper necks 4 of the gas bottles are retainingly engaged and partially embraced by a pair of clamp bars 15 having oppositely outwardly facing channel shaped cross section and having opposed concave neck-gripping ends 16 connected by spaced parallel center portions 17 with holes 18 formed therethrough. One of the clamp bars has a nut 19 welded or secured over the hole 18 therein which receives the threaded rear end of an elongated clamp screw 20 passed through the holes 18 and the eye 12 of the hold down rod. The thrust washer 21 secured near the forward end of the clamp screw by swaged ears 22 permits the screw 20 to draw the clamp bars 15 tightly against opposite sides of the upper necks 4 while the hold down rod 11 prevents upward displacement of the clamp bars and the gas bottles. The integral handle end 23 or other suitable handle on the clamp screw permits manipulation of the screw.

Toward its upper end the hold down rod 11 is provided with thread 24 that is projected or extended beyond the adjacent portion of the rod as by being rolled into the body of the rod. The enlarged or projecting character 25 of the thread 24 permits a support nut 25 to be installed on the hold down rod quickly without threading the full length of the rod. The support nut 25 supports the laterally or horizontally turned foot 26 on the lower end of a regulator support plate 27. The hold down bolt passes through a hole 28 in the foot while the clamp screw 20 passes through a hole 29 in the upstanding portion of the regulator plate. The regulator plate is thus securely supported and restrained against vertical and lateral displacement in any direction. The upper end of the regulator support plate 27 carries the standardized regulating valve 30 and delivery connections 31 of the gas bottle installation. A minimum of parts thus releasably secures the gas bottles in position and support the regulator connections on the frame of the trailer.

What is claimed is new is:

1. A gas bottle rack for trailers comprising a flat base plate with upstanding front and rear flanges, said flanges defining spaced notches sized to retainingly engage lower necks of a pair of gas bottles, means for clamping said base plate to the frame of a trailer, an upwardly offset boss in the center of said plate between said notches and defining a central hole, a hold down rod extending upwardly through said hole and having a retaining nut on its lower end, an eye on the upper end of said hold down rod, a clamp screw passed through said eye, a pair of clamp bars having opposed concave end portions adapted to retainingly grip upper necks of a pair of gas bottles and having spaced central portions with holes therein receiving said clamp screw, a nut secured to one of said clamp bars and providing a thread thereon engageable with said clamp screw, an abutment on said clamp screw coacting with the other of said clamp bars, a regulator support plate having a hole near its lower end passing said clamp screw, a laterally turned foot on said regulator plate having a hole therein passing said hold down bolt, a threaded portion near the upper end of said hold down bolt and of larger diameter than the remainder of the hold down bolt, and a support nut on said threaded portion supportingly engaging the underside of said foot.

2. A gas bottle rack for trailers comprising a flat base plate with upstanding front and rear flanges, said flanges defining spaced notches sized to retainingly engage lower necks of a pair of gas bottles above the top surface of the plate, means for clamping said base plate to the frame of a trailer, said plate between said notches defining a central hole, a hold down rod extending upwardly through said hole and having a retaining nut on its lower

end, an eye on the upper end of said hold down rod, a clamp screw passed through said eye, a pair of clamp bars having opposed concave end portions adapted to retainingly grip upper necks of a pair of gas bottles seated in said notches and having spaced central portions with holes therein receiving said clamp screw, a nut engaged with one of said clamp bars and engageable with said clamp screw, an abutment on said clamp screw coating with the other of said clamp bars, a regulator support plate having a hole near its lower end passing said clamp screw, a laterally turned foot on said regulator plate having a hole therein passing said hold down bolt, a threaded portion near the upper end of said hold down bolt and of larger diameter than the remainder of the hold down bolt, and a support nut on said threaded portion supportingly engaging the underside of said foot.

3. A gas bottle rack for trailers comprising a flat base plate with upstanding front and rear flanges, said flanges defining spaced notches sized to retainingly engage lower necks of a pair of gas bottles above the top surface of the plate, means for clamping said base plate to the frame of a trailer, said plate between said notches defining a central hole, a hold down rod extending upwardly through said hole and having a retaining means on its lower end, an eye on the upper end of said hold down rod, a clamp screw passed through said eye, a pair of clamp bars having opposed concave end portions adapted to retainingly grip upper necks of a pair of gas bottles seated in said notches and having spaced central portions with holes therein receiving said clamp screw, a nut engaged with one of said clamp bars and engageable with said clamp screw, an abutment on said clamp screw coating with the other of said clamp bars, a regulator support plate, a laterally turned foot on said regulator plate having a hole therein passing said hold down bolt, a threaded portion near the upper end of said hold down bolt, and a support nut on said threaded portion supportingly engaging the underside of said foot.

4. A gas bottle rack for trailers comprising a flat base plate, means for clamping said base plate to the frame of a trailer, said plate defining a central hole, a hold down rod extending upwardly through said hole and having a retaining means on its lower end, an eye on the upper end of said hold down rod, a clamp screw passed through said eye, a pair of clamp bars having opposed concave end portions adapted to retainingly grip upper necks of a pair of gas bottles seated on said plate and having spaced central portions with holes therein receiving said clamp screw, said clamp screw coating with said clamp bars to draw the bars together, a regulator support plate having a hole near its lower end passing said clamp screw, a laterally turned foot on said regulator plate having a hole therein passing said hold down bolt, a threaded portion near the upper end of said hold down bolt, and a support nut on said threaded portion supportingly engaging the underside of said foot.

5. A gas bottle rack for trailers comprising a flat base plate, means for clamping said base plate to the frame of a trailer, said plate defining a central hole, a hold down rod extending upwardly through said hole and having a retaining means on its lower end, an eye on the upper end of said hold down rod, a clamp screw passed through said eye, a pair of clamp bars having opposed concave end portions adapted to retainingly grip upper necks of a pair of gas bottles seated on said plate and having spaced central portions with holes therein receiving said clamp screw, said clamp screw coating with said clamp bars to draw the bars together, a regulator support plate, a laterally turned foot on said regulator plate having a hole therein passing said hold down bolt, and a support nut on said hold down rod supportingly engaging the underside of said foot.

6. A gas bottle rack for trailers comprising a base plate having projections thereon laterally engageable with the lower ends of a pair of gas bottles, a pair of clamp bars having opposed concave ends engageable with the upper ends of said bottles, screw means engaged between the central portions of said clamp bars to draw the clamp bars together, a hold down rod engaged with said base plate and having an eye on its upper end surrounding said screw means, a regulator support bracket vertically interlocked with said screw means and projecting thereabove and horizontally interlocked with said hold down rod, and a support on said hold down rod supporting the lower end of said regulator bracket.

7. A gas bottle rack for trailers comprising a base plate having projections thereon laterally engageable with the lower ends of a pair of gas bottles, a pair of clamp bars having opposed concave ends engageable with the upper ends of said bottles, screw means engaged between the central portions of said clamp bars to draw the clamp bars together, a hold down rod engaged with said base plate and having an eye on its upper end surrounding said screw means, a regulator support bracket horizontally interlocked with said hold down rod, and a support on said hold down rod supporting the lower end of said regulator bracket.

8. A gas bottle rack for trailers comprising a base plate engageable with the lower ends of a pair of gas bottles, a pair of clamp bars having opposed concave ends engageable with the upper ends of said bottles, screw means engaged between the central portions of said clamp bars to draw the clamp bars together, a hold down rod engaged with said base plate and having an eye on its upper end surrounding said screw means, a regulator support bracket horizontally interlocked with said hold down rod, and a support on said hold down rod supporting the lower end of said regulator bracket.
